UNITED STATES PATENT OFFICE.

JOHN B. THOMPSON, OF ARLBERG, ARKANSAS.

BROODER.

988,747.

Specification of Letters Patent.

Patented Apr. 4, 1911.

Application filed August 1, 1910. Serial No. 574,847.

To all whom it may concern:

Be it known that I, JOHN B. THOMPSON, a citizen of the United States, residing at Arlberg, in the county of Stone and State of 5 Arkansas, have invented certain new and useful Improvements in Brooders, of which the following is a specification, reference being had to the accompanying drawings.

This invention relates to brooders and has 10 for its object to produce a simple and inexpensive device of this character and to improve its construction and increase its efficiency.

Another object is to provide a brooder 15 having a new and novel heating means whereby a steady and even circulation of heat may be distributed throughout the brooder, said brooder having an improved hoverer arranged therein to provide a soft 20 covering against which the chicks may nestle whereby the liability of them crowding together and suffocating is eliminated.

A further object resides in the provision 25 of an improved lamp support arranged exteriorly of the brooder, said lamp being adapted to heat water in a suitable reservoir, and means for conducting the heated water through suitable pipes or ducts to the interior of the brooder.

30 A still further object is to provide a brooder having a cold air compartment arranged at one end thereof, said end of the brooder being open so that the chicks may have access to said compartment.

35 With these and other objects in view, the invention consists of the novel features of construction and the combination and arrangement of parts hereinafter fully described and claimed, and illustrated in the 40 accompanying drawings, in which—

Figure 1 is a perspective view of a brooder constructed in accordance with my invention, the top thereof being removed; Fig. 2 is a vertical longitudinal section; Fig. 3 is 45 a section taken on the line 3—3 of Fig. 2; Fig. 4 is a section taken on the line 4—4 of Fig. 3; Fig. 5 is a detail perspective view of the hovering member removed; and Fig. 6 is a plan view of a slightly modified arrangement of the heating pipes.

50 Referring more particularly to the drawings 5 indicates a frame. To three sides of

this frame sheet metal plates 6 are secured. The bottom of the frame is open and rests directly upon the ground or upon a removable sheet metal flooring if it is desired to employ the same. The top of the frame is closed by means of the hinged cover 7. This cover may be lifted to allow the entrance of air and sunlight to the interior of the 60 brooder in fair weather. The frame 5 is preferably formed of a plurality of strips of material nailed together, and to the upper strips the pieces of fabric 8, preferably wool, are secured and cover the sheet metal sides 65 6. This soft fleecy material prevents contact of the bodies of the chicks with the cold sides of the brooder. The piece of fabric 8 extending across the front of the brooder has its free lower edge cut to provide a 70 plurality of tabs 9 between which the chicks may extend their heads into the comparatively cool atmosphere outside of the casing of the brooder.

The front end of the brooder has hinged 75 to its opposite sides the doors 10. These doors are arcuate in plan and when brought together, as shown in Fig. 3, they form a substantially semi-circular inclosure. To one of the doors a double hook 11 is pivoted, 80 the hooks 11^a and 11^b of which are adapted to engage in an eye 12 secured to the other door. A removable top 13 is provided for this exterior compartment and is preferably constructed of sheet metal and formed with 85 a flange 13' having an aperture in each end for engagement with the hooks 14 secured in the frame of the brooder. In moderate weather this cover may be removed. When the hook 11^a is engaged in the eye 12, the 90 doors 10 are drawn closely together to prevent the escape of the chicks from the cold air compartment, while the free slotted lower end of the fabric lining 8 secured across the front end of the brooder will permit the 95 chicks to freely pass from the heated interior to the comparatively cold exterior compartment. When the other of the hooks 11^b is engaged with the eye 12, the ends of the doors will be slightly separated, as 100 shown in Fig. 1, so as to permit the chicks to pass through said doors to the outside. If a hen is being used, she will be kept a prisoner in the brooder, the space between

the ends of the doors being insufficient to allow her to pass therethrough.

A hovering member 15 is supported in the upper end of the brooder frame and comprises a rectangular frame to which are secured the depending hover curtains 16. These curtains are cut or slitted similar to the front lining fabric 8, and a sheet of fabric 17 is also secured to the members of the hovering frame and is of such size as to sag or depend from the frame members into the brooder. This fabric sheet 17 serves to retain the heat within the brooder which is thrown off from the bodies of the chicks so that when the temperature is comparatively mild, the use of artificial heating means is rendered unnecessary. To opposite sides of the hovering frame the rods 18 are secured and have their ends extended upwardly and outwardly, as shown at 18', for engagement in the recesses 19 formed in the upper edges of the brooder frame. In this manner the hovering member is supported within the brooder and may be easily and quickly removed when desired. To the fabric sheet 17 a thermometer 20 may be secured and by simply lifting the top 7, the temperature of the brooder may be determined at a glance so that the heat supplied thereto may be regulated accordingly. The hover curtains 16 are of very soft and fleecy material so that the chicks may nestle against the same and be closely covered by the slitted ends of the curtains. The danger of the chicks massing together in one place for warmth and possible suffocation of numbers of the chicks as a consequence thereof is thus avoided. In extremely cold weather, however, it is necessary to provide additional heating means for the brooder.

Heretofore lamps have been arranged within the brooder inclosed in suitable casings, but the fumes of the oil which are emitted from the lamp often cause the death of large numbers of the chicks. In order to obviate this great disadvantage, I provide the new and novel heating means which will now be described in detail. To the above end I provide a tank or casing 21 which comprises the spaced walls 22 secured together at their upper and lower ends in any desired manner. These walls are arranged in parallel relation and provide a water space between them in which the water to be heated is poured through an inlet spout 23 provided in the top of the casing. This inlet spout may be closed by means of a suitable cap threaded thereon. Spaced vertical cylindrical openings 24 are formed between the inner walls of the casing and are connected by means of the transverse passage 25. One of the openings 24 is adapted to receive a lamp 26 which is supported upon a base board 27 carried by a casing 28 which

surrounds the water reservoir and abuts 65 against the end of the brooder. This casing consists simply of three side members and is open both at its top and bottom. The lamp receiving opening is adapted to be closed at its top by means of a removable 70 closure plate 29 held thereon in the guides 30 extending over the upper end of said opening. The other of the openings 24 is closed at its bottom and a frusto-conical extension 31 extends upwardly from the upper 75 end thereof. The fumes from the lamp are adapted to pass through the connecting passage 25 between the openings 24 and conducted from the heater above the same through this frusto-conical extension. The 80 danger of these fumes circulating around the brooder or entering beneath the cover is thereby eliminated.

A duct or pipe 32 is arranged in the upper end of the brooder frame and rests upon the hovering member, thereby serving to retain the hovering member in position by its weight. This water receiving pipe is preferably rectangular in form and adjacent to its ends is connected by means of 90 the short pipes 33 with the annular water space formed in the heater. Thus, as the water is heated it circulates through said pipes and distributes its heat evenly within the top of the brooder. This heat does not 95 communicate directly with the bodies of the chicks but through the hovering curtains and the felt lining of the brooder, thereby simulating as nearly as possible the natural warmth of a hen's body.

It will be noted that the rear upper edge of the frame of the brooder is recessed to receive the short pipes 33, one of said pipes communicating with the water reservoir at one end while the other pipe connects therewith at the opposite end of the heater. The first named pipe is disposed in line with the heating lamp and the water passing therethrough is consequently heated to the highest degree and it is returned to the reservoir through the other of the pipes 33 at the opposite end of the heater. Thus, a constant circulation of the water through the pipes 32 and 33 to the heater is maintained. The degree to which the water is heated 110 may be regulated by adjusting the wick of the lamp and moving the closure plate 29 arranged on the upper end of the opening 24 above the lamp to open or close said opening to a greater or less degree.

A brooder constructed as above described is adapted to house sixty-four chicks and in a larger sized brooder for containing from one hundred to two hundred chicks, I would preferably employ the arrangement of heating pipes shown in Fig. 6. In this form of the device the outer heating pipes 31' have arranged within the same a

second smaller water conducting series of pipes 34. These last named pipes are connected at opposite points by means of the pipes 35 with the outer pipe frame which in turn is connected to the heater as previously described in the main form of the device. This arrangement of the pipes will furnish ample heat for a large sized brooder and distribute the same evenly throughout the 10 interior thereof.

From the foregoing it will be seen that I have devised a very novel and efficient brooder whereby the chicks may be warmly housed in the coldest weather. When the 15 weather is very mild, the hovering member may be removed and a hen employed if desired, though of course, it will be understood that the primary object of the invention is to provide means for properly heating 20 the brooder whereby the necessity of using the hen for mothering the chicks is eliminated. The brooder is very simply constructed and may be manufactured at a comparatively low cost. It is also highly 25 durable in operation and requires but little care and attention as it is capable of being quickly and thoroughly cleaned and thus kept at all times in a sanitary condition.

While I have shown and described the 30 preferred embodiment of the invention, it will be understood that the same is susceptible of many minor modifications without departing from the essential features or sacrificing any of the advantages thereof.

Having thus described the invention what is claimed is:

1. A brooder comprising a casing having an open side, a fabric lining for said casing, said lining at the open side of the casing 40 being slitted to permit access thereto, a compartment arranged exteriorly of the casing and associated with the front open side thereof, a hovering member supported in the upper end of the casing and depending into 45 the same, heat distributing means arranged in the casing above the hovering member and means for supplying a heating medium to the distributing means.

2. A brooder comprising a rectangular 50 frame structure, sheet metal plates covering three sides of said structure, the other side thereof being open, a hovering member removably supported on said frame structure and depending into the brooder between the 55 sides thereof, heat distributing pipes arranged above said hovering member, a water reservoir arranged exteriorly of the brooder, pipes connecting said reservoir to the heat distributing pipes and a heating element associated with said reservoir to heat 60 the water therein.

3. A brooder comprising a rectangular casing open on one side, doors hinged to the open side thereof, means for closing said

doors to form an exterior compartment, a removable cover on the open end of the brooder extending above said doors, a hovering member removably supported in the brooder and spaced from the sides thereof, heat distributing pipes arranged above the hovering member, a water reservoir arranged exteriorly of the brooder, connections between said pipes and reservoir, a casing inclosing the reservoir, and a heating element associated with said reservoir to heat 75 the water therein.

4. A brooder comprising a casing open on one side, a fabric lining for said casing, said lining at the open side of the casing being slitted at its lower end, doors hinged to the 80 open end of said casing, means for securing said doors together to form an exterior cold air compartment, a removable cover extending over said doors, a hovering member supported within the casing, said member comprising a frame disposed in spaced relation to the sides of the casing, hovering curtains secured to the frame slitted at their lower ends, and a hinged cover for said casing. 90

5. A brooder comprising a casing open on one side, a fabric lining for said casing, said lining at the open side of the casing being slitted at its lower end, doors hinged to the 95 open side of said casing, means for securing said doors together to form an exterior cold air compartment, a removable cover extending over said doors, a hovering member supported within the casing, heat distributing means arranged in the casing, water heating 100 means disposed exteriorly of the casing and connected to said distributing means, and a hinged cover for said casing.

6. A brooder comprising a casing open on one side, a fabric lining for said casing 105 extending on all sides thereof, said lining being slitted at the open side of the casing, a hovering member removably supported in the casing, heat distributing pipes arranged above said member, a water reservoir arranged exteriorly of the casing, pipes connecting said reservoir to the heat distributing pipes at opposite ends thereof, a casing for said water reservoir, said reservoir having spaced vertical openings therein, a lamp supported by said casing and positioned in one of said openings, said openings being connected by a passage, an adjustable closure for the lamp opening, the other of said openings having a 115 closed bottom and an extension at its top adapted to exhaust the fumes from the lamp, and a hinged cover for said casing. 120

7. A brooder comprising a casing open on one side, doors hinged to the open side 125 of said casing, means for securing said doors together to form an exterior cold air compartment, a hovering member removably

4
suspended within the casing, and heat distributing means removably arranged above the hovering member.

8. A brooder comprising a casing open on one side, a cold air compartment arranged on the open side of the brooder, a fabric lining for said casing, said lining at the open side of the casing being slitted at its lower

end, and hot water pipes removably arranged within said casing.

10

In testimony whereof I hereunto affix my signature in the presence of two witnesses.

JOHN B. THOMPSON.
